Patented June 8, 1920.

UNITED STATES PATENT OFFICE.

JOHAN SKINDERVIKEN, OF CHICAGO, ILLINOIS, ASSIGNOR OF ONE-HALF TO OLAUS EKLO, OF CHICAGO, ILLINOIS.

CIGAR HOLDER AND SAVER.

1,342,512.

Specification of Letters Patent.

Patented June 8, 1920.

Application filed October 18, 1918. Serial No. 258,732.

To all whom it may concern:

Be it known that I, JOHAN SKINDERVIKEN, a subject of the King of Norway, having declared my intention to become a citizen of the United States, residing at Chicago, in the county of Cook and State of Illinois, have invented certain new and useful Improvements in Cigar Holders and Savers, of which the following is a specification.

10 My invention relates to a container adapted to be carried in a pocket of the user's clothing to receive lighted cigars and cigarettes when conditions arise which make it necessary, advisable or desirable for the

15 smoker to temporarily discontinue its consumption, to avoid premature discard.

I am aware that various types of holders for the purpose mentioned are known. Such types however have a means into which the 20 butt end of the cigar or cigarette is pushed, which feature renders the constructions impractical as the butt ends of lighted cigars and cigarettes are moistened by the saliva of the mouth and if they contact with and are 25 pressed against any abutment, such butt ends are crushed and the cigar or cigarette wrapper is broken. The main object of the present invention is to overcome such an objection, and one definite servient object is to 30 provide a means to engage and hold a cigar or cigarette which is movable laterally into engagement with the cigar or cigarette so that sliding movement of the cigar or cigarette against the holding means is obviated.

35 With the above, and additional objects, which will appear hereinafter, the invention has been embodied in one preferred form as illustrated in accompanying drawings.

In the views of said drawings, illustrating 40 the improved cigar or cigarette holder,

Figure 1 is a front elevation;

Fig. 2 is a vertical sectional view with the sections of the casing or holder detached;

Fig. 3 is a vertical sectional view, taken at 45 right angles to Fig. 2, and showing a cigar carried thereby;

Fig. 4 is a bottom view of the closure section of the holder, and

Fig. 5 is a top view of the closure section 50 of the holder.

In carrying out the invention, a casing or holder of any suitable material and construction is used. The form shown, consists of a main container or holder section 6 and a 55 closure section 7. These sections may be

connected together in any suitable manner, which will permit ready detachment. For instance, the upper end of the container or section 6 is constructed to provide a wall 8 adapted to extend into the closure section 7, 60 as best shown in Fig. 3, and frictionally engage the inner surface of the wall thereof, so that the sections will be held in coupled relation by frictional contact. By way of example, the sections 6 and 7 may be made 65 of any suitable metal and the interior surface thereof may be lined with asbestos or similar material at 9 and 10, to confine the heat from the cigar or cigarette and insulate the clothing of the user from such heat. It 70 will be noted, particularly in Fig. 3, that the lower portion of the asbestos 10 is disposed intermediate the wall 8 and the adjacent portion of the closure 7 when the sections 6 and 7 are connected together. Better frictional contact may be obtained, with the asbestos disposed between said wall 8 and the closure.

A suitable holding or clasp means for the cigar or cigarette is mounted by one of the 80 sections, and preferably by the closure section 7. The means shown comprise an arm 11 and an arm 12, having jaws 13, provided with serrations at 14, if desired, to grip a cigar or cigarette 15 as in Fig. 3. Arm 11 is 85 provided with an eyelet or journal at 16 while the arm 12 is provided with an eyelet or journal 17. Each arm 11 and 12 is preferably metallic. A pivot 18 passes through the journals 16 and 17 to mount the arms 11 90 and 12 for swinging movement, and the terminals of the pivot 18 are preferably turned up and soldered or otherwise secured to the closure 7. Above the pivot 18, an enlarged slot 19 is preferably provided through the 95 section 7 and extending through and beyond said slot, are fingers 20, integral with the arms 11 and 12 and their journals. These fingers 20 are normally urged apart by means of a coil spring 21 surrounding an 100 arcuate rod 22 fastened rigidly at one end as at 23, to one of the fingers, and projecting loosely at its other end through an opening in the other finger, as at 24. It will be seen that by the operator's fingers pressing the 105 fingers 20 together, the jaws 13 will be spread apart so as to release or be ready to receive a cigar. Spring 21 normally urges the arms 11 and 12 into gripping engagement with the cigar. The walls at the slot 110

19, limit the extent to which the arms may move under the urgency of spring 21.

This article may be carried in a pocket of clothing and should the user wish, it may be withdrawn, and the sections 6 and 7, pulled apart. The user's fingers may then press the fingers 20 toward each other in order to separate the jaws 13, place the butt end of a cigar between them and then release them so that the spring 21 will urge the jaws into clamping engagement with the cigar in order to retain it. Attention is called to the fact that the serrations 14 may be used or dispensed with at pleasure, and that the serrations are brought into engagement with the cigar at a portion necessarily broken by moisture of the mouth. Closure 7 afterward may be attached by sliding movement, to the main section 6, with the cigar disposed therein as shown in Fig. 3. The operation of removal is of course just the reverse namely, removing the closure 7 and the cigar, and then manipulating the fingers 20 to release the cigar.

25 Particular attention is called to the fact that the cigar is not pressed against any part or abutment in the act of attaching it or disposing it in the holder. The jaws 13 move laterally of the cigar and there is therefore no danger of fracturing the cigar wrapper at an undesirable point or of crushing the butt end.

Since merely one preferred embodiment has been illustrated and described, it is to be understood that changes in the details of construction may be resorted to without departing from its spirit and scope.

I claim:

1. A cigar holder having holding means,

said holder having a slot, said holding means comprising arms extending through said slot, means to pivot said arms, a rod secured to one of said arms and suspended loosely relatively to the other arm, and a spring surrounding said rod and urging said arms apart above the pivot.

2. A cigar holder having holding means and a slot, said holding means comprising arms movable in said slot, said arms having portions extending at obtuse angles to each other and with journals at their junctions, means on which said journals are pivoted, one portion of each arm being provided with cigar-gripping means, the other portion of each arm serving as manipulating fingers, a rod rigid with one of said fingers and loose relative to the other finger, and a spring surrounding said rod and normally urging said fingers apart.

3. A cigar holder having holding means and a slot, a pivot member below said slot, arms having journals mounted on said pivot member, said arms having downwardly extending portions provided with inwardly extending cigar-gripping jaws, said arms being provided with upwardly extending fingers, one of said fingers having an opening therein, a curved rod rigid with the other finger and extending loosely through said opening, and a spring surrounding the rod to urge said fingers apart.

In testimony whereof, I have affixed my signature in the presence of two witnesses.

JOHAN SKINDERVIKEN.

Witnesses:

DAVID WOLF,
S. S. BECKLEY.
